United States Patent Office.

THEODORE R. SLOAN, OF BROOKLYN, NEW YORK.

Letters Patent No. 105,856, dated July 26, 1870.

IMPROVEMENT IN PANTALOONS.

The Schedule referred to in these Letters Patent and making part of the same

To all whom it may concern:

Be it known that I, THEODORE R. SLOAN, of Brooklyn, in the county of Kings and State of New York, have invented a new and useful Improvement in Pantaloons; and I do hereby declare the following to be a full, clear, and exact description thereof, which will enable those skilled in the art to make and use the same, reference being had to the accompanying drawing forming part of this specification, in which drawing—

Figure 1 represents a front view of my invention, showing the pantaloons turned inside out.

Figure 2 is a longitudinal section of the same.

Figure 3 is a cross-section of the same.

Similar letters indicate corresponding parts.

This invention consists in the arrangement of a strengthening piece across the knee-parts of pantaloons, said strengthening piece being fastened on the seams, and being made, by preference, somewhat narrower than that part of the pantaloons to which it is attached, in such a manner that the strain exerted by the knees on the pantaloons, particularly if such pantaloons are worn by persons of a sedentary occupation, is intercepted by the strengthening piece, and the knee-part of the pantaloons is prevented from stretching and from bagging out.

In the drawing—

The letter A designates a pair of pantaloons, the knee-parts of which are protected on the inside by the strengthening pieces a. These pieces are, by preference, made of a stiff fabric, and they are fastened at their upright edges to the side seams of the pantaloons, the horizontal edges of said strengthening pieces being left free and detached.

Said strengthening pieces are made, by preference, somewhat narrower than that part of the pantaloons over which they extend, so as to leave a crescent-shaped space, b, (see fig. 3.)

By these means, the fabric from which the pantaloons are made is relieved from the strain exerted thereon by the knees of the person wearing said pantaloons, particularly in sitting down, and, while the knee of ordinary pantaloons is liable to stretch and bag out, thereby marring the shape of the article, my pantaloons retain their original shape for a long time.

I am aware that it is not new to place on pantaloons pieces of rubber or other elastic material, to prevent bagging at the knee.

What I claim as new, and desire to secure by Letters Patent, is—

The combination, with the knee-part of pantaloons, of strengthening pieces a, secured at the seams thereof, and stretched from said seams, in order to form spaces b between the pantaloons and pieces, so that the knees will press the pieces into the spaces without pressure against the pantaloons, as and for the purpose described.

This specification signed by me this 3d day of June, 1870.

THEO. R. SLOAN.
